GAME BOARD

Henry J. Hebert, 926 Granby Road,
Aldenville, Mass. 01001

Filed June 10, 1966, Ser. No. 2,636

Term of patent 14 years

(Cl. D34—5)

FIG. 1 is a top plan view of a game board showing my new design; and

FIG. 2 is a sectional view taken along line 2—2 of FIG. 1.

I claim:

The ornamental design for game board, as shown.
